UNITED STATES PATENT OFFICE.

FRANK J. HERRICK, OF NEW BRITAIN, CONNECTICUT.

DESIGN FOR A BELT-CLASP.

SPECIFICATION forming part of Design No. 19,578, dated January 14, 1890.

Application filed December 20, 1889. Serial No. 334,443. Term of patent 7 years.

To all whom it may concern:

Be it known that I, FRANK J. HERRICK, a citizen of the United States, residing at New Britain, in the county of Hartford and State of Connecticut, have invented and produced a new and original Design for Belt-Clasps, of which the following is a specification, reference being had to the accompanying drawings, forming a part thereof.

Figure 1 is a front view of a belt-clasp showing my design. Fig. 2 is a detail edge view of the same.

The leading feature of my design consists of an oblong loop *a*, of metal, having the surface formed to represent a series of bead-like devices *b* strung together, with a bar *c* extending between opposite parts of the loop-like structure. The edges of the loop form a scalloped line, and depressions in the surface

of the loop extend from side to side across 20 the face of the loop from the deepest part of the indentations in the bounding lines, the surface of the loop between such cross-lines being formed in curved surfaces that give to the loop the appearance of a chain or string 25 of beads.

What I claim is—

The design for a clasp-loop herein shown and described, the same comprising an oblong frame with central cross-piece and having the 30 main surface of the frame formed in a series of rounded or globular parts, all substantially as described.

FRANK J. HERRICK.
